(57) **CLAIM**

The ornamental design for the clip, as shown and described herein.

DESCRIPTION

FIG. 1 is a side view of a clip, in accordance with the new design;

FIG. 2 is a perspective view, showing the opposite side;

FIG. 3 is a side view of a second embodiment of the clip;

FIG. 4 is a side view of the clip of FIG. 3, wherein the clip is open; and,

FIG. 5 is a perspective view of the clip of FIG. 3, showing the opposite side.

The broken line showing of the folding knife is provided for purposes of environment and forms no part of the claimed design.
